Primary Examiner — Kathleen L Jones

(57) **CLAIM**

The ornamental design for a dual screen display, as shown and described.

DESCRIPTION

FIG. 1 is a front and top perspective view of a dual screen display, showing our new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view thereof, shown in an alternative position;

FIG. 10 is another perspective view thereof, shown in an alternative position; and,

FIG. 11 is an enlarged perspective view of detail “11” identified in FIG. 1.

The dashed lines in the figures illustrate portions of the dual screen display that form no part of the claimed design. The dash dot dash lines in FIGS. 1 and 11 are for the purpose of illustrating the enlarged view indicators and form no part of the claimed design.

1 Claim, 11 Drawing Sheets
